FLUORESCENT LIGHTING

Edwin G. Gaynor, Fairfield, and Harold K. Andrews, Stratford, Conn.

Application October 1, 1943, Serial No. 504,596

19 Claims. (Cl. 315—100)

1

This invention relates to new and useful improvements in lighting apparatus and has particular relation to fluorescent lighting.

An object of the invention is to provide a means whereby fluorescent lamps may be easily and quickly removed from and replaced in a fixture whether the latter is in a high or other place not readily accessible, or otherwise.

Another object is to provide a lighting apparatus employing a fluorescent lamp and wherein all contact parts are substantially completely enclosed thus reducing fire hazard.

A further object is to provide a fluorescent lighting apparatus including a starter means arranged and constructed to insure starting of the lamp although the latter may be located in a low temperature area.

An additional object is to provide a fluorescent lighting apparatus including two part separable sockets.

Another object is to provide sockets for fluorescent lighting apparatus and which sockets include one concealed and one exposed part the latter being provided with a cover which may be of any desired appearance and/or design and of any desired material to the end that esthetic differences among designers of lamps may find expression.

Yet another object is to provide a fluorescent lighting apparatus as indicated and which in addition to a thermal starter apparatus includes a thermal relay means for opening the supply line on repeated attempts and failures on the part of the starter whereby the current will not remain on in futile attempts of the starter to start an exhausted lamp.

A further object is to provide a two part fluorescent lamp socket as indicated and wherein one of such parts is removable from a fixture along with the lamp and wherein the thermal starter of the lighting system is mounted within said removable socket part.

An additional object is to provide a fluorescent lighting apparatus including the lamp and the necessary sockets and wherein the sockets are of such construction that the lamp may be applied to and removed from the fixture through the use of extension means to the end that the climbing on chairs, catwalks, ladders or the like to reach a lighting fixture may be avoided.

Other objects and advantages will become apparent from a consideration of the following detailed description taken in connection with the accompanying drawings wherein a satisfactory embodiment of the invention is shown. How-

2

ever, it is to be understood that the invention is not limited to the details disclosed but includes all such variations and modifications as fall within the spirit of the invention and the scope of the appended claims.

In the drawings—

Fig. 1 is a side elevational view of a fixture and a fluorescent lamp the latter being mounted by the sockets of the present invention;

Fig. 2 is a bottom plan view of the device of Fig. 1;

Fig. 3 is a side elevational view of the lamp and the detachable portions or plugs of the present detachable or two part sockets;

Fig. 4 is an elevational view showing one side of the plug of one socket;

Fig. 5 is a similar view showing the other side of said plug;

Fig. 6 is a view similar to Fig. 4 but showing the plug of the other socket;

Fig. 7 is a view showing the reverse side of the plug of Fig. 6;

Fig. 8 is a view partly in section and partly in elevation and showing the plug and base assembly of the socket at one end of a fluorescent lamp, the cover of the plug being indicated by dotted lines and the parts being shown on a larger scale;

Fig. 9 is a sectional view taken as along the plane of the line 9—9 of Fig. 8;

Fig. 10 is a transverse sectional view taken as along the plane of the line 10—10 of Fig. 9;

Fig. 11 is a similar view taken as along the plane of the line 11—11 of Fig. 9;

Fig. 12 is a sectional view taken as along the plane of the line 12—12 of Fig. 9;

Fig. 13 is a front elevational view of one of the socket bases or base portions;

Fig. 14 is a bottom plan view of such base;

Fig. 15 is a top plan view of such base the usual cover or closure being omitted;

Fig. 16 is a longitudinal sectional view through said base, the view being along the line 16—16 of Fig. 15;

Fig. 17 is a transverse sectional view through said base the view being taken along the plane of the line 17—17 of Fig. 15;

Fig. 18 is a similar view taken along the plane of the line 18—18 of Fig. 15;

Fig. 19 is a perspective view of one of the contacts removed from said base;

Fig. 20 is a view similar to Fig. 8 but showing the two part socket at the other end of said fluorescent lamp;

Fig. 21 is a longitudinal central sectional view taken as along the line 21—21 of Fig. 20; and

Fig. 22 shows the wiring diagram.

Referring in detail to the drawings the invention is illustrated using a fixture of any desired style or type, herein generally designated 10, and including a hollow elongated body having a bottom or lower wall 11. Mounted on the fixture 10 and disposed at the lower side thereof is a fluorescent lamp 12. It is to be understood that the fixture 10 may be of the shape or design and the construction desired and that generally speaking its length is determined by the length of the fluorescent lamp with which it is to be used.

Mounted on the fixture 10 or otherwise conveniently located is a switch 13 including an operating handle or manual 14. When the fixture 10 is located in a high place or in a place inconvenient for any other reason the switch 13 will not be mounted on the fixture but will be mounted in some convenient spot. In the fixture wall 11 are a pair of holes 15 in predetermined spaced relation and adapted for use in connection with an extension means for applying a lamp 12 to the fixture when the latter is in a high place or the like. Such an extension means or applicator is disclosed in detail in my companion application, Serial Number 503,912, filed September 27, 1943. This application issued March 13, 1945, as U. S. Patent No. 2,371,437.

Specifically the lamp 12 is mounted on the fixture 10 by means of separable or two part sockets 16 and 17 located at the respective ends of the lamp. Socket 16 includes a base 18 and a plug 19 while socket 17 includes a base 20 and a plug 21. The bases 18 and 20 are of identical construction but there is some difference between the plugs 19 and 21. However, in each case the plug is, physically and electrically, readily connected with and disconnected from the base whereby the lamp 12 may be easily and quickly mounted on and removed from the fixture 10 and when mounted thereon will be electrically connected as will later appear in detail.

Lamp 12 is of standard construction and includes an elongated tubular glass body having the usual end caps 22 and 23 through which extend contact pins or tangs for insertion into engagement with contacts of sockets. Such pins or tangs are arranged in pairs and as shown pins or tangs 24 and 25 at one end of the lamp constitute a pair while the pins or tangs 26 and 27 at the other end of the body constitute the other pair. These pins or tangs are connected with filaments 28 and 29 respectively (see Fig. 22), located at the respective ends of the lamp and within the glass body of the latter.

Since the bases 18 and 20 are of substantially identical construction but one, the base 18, will be described in detail although it is to be understood that such description applies to both bases and it is noted that the same reference characters have been applied to the parts of such bases. Base 18 includes a body 30 of insulating material. This body is open at its upper side and on its lower or under side is provided with a projecting portion or neck 31 rectangular in shape and in fact of a shape and size to enter and rather snugly fit in the opening usually provided in a fluorescent lamp fixture for the reception of a portion of a socket.

A pair of entrance slots 32 through the neck 31 communicate with chambers 33 and 34 within the body 30 and such chambers are open at their upper sides as clearly shown in Fig. 16. A wall 35 stops short of the upper edge of the insulating body 30 but serves to separate the chambers 33

and 34. About midway of the height of the body 30 the chambers 33 and 34 are laterally enlarged providing shoulders 36 and 37 (Figs. 8, 13, 15 and 16) and such chambers are also enlarged rearwardly providing shoulders 38 and 39 (Figs. 17 and 18). Thus shoulders 36 and 38 together form an L-shaped surface while shoulders 37 and 39 provide a similarly shaped surface. The foot portions of such shaped surfaces are in opposing relation.

Each of the mentioned chambers receives a contact and while these contacts are of the same construction they are arranged in opposing relation and are given separate reference numbers in the assembly drawings. Thus in chamber 33 there is located contact 40 while in chamber 34 there is mounted contact 41. Each such contact (see Fig. 19) includes a mounting portion or plate 42 of generally L-shape from the inner edge of an arm portion of which depends an arm 43 bent upon itself at 44 providing a portion 45 extending upwardly at an angle. The upper portion 46 of such arm is again bent and extends back at an angle as toward but with its free edge 25 above the plate 42. Attention is directed to the fact that portion 46 is at a sharper angle than portion 45 and the purpose of this will be set forth.

When located in the respective chambers 33 and 34 the contacts 40 and 41 have their plate portions 42 disposed on the L-shaped surfaces provided by the shoulders 36 and 38 and 37 and 39 respectively. The arm portions of the contacts then extend downwardly so that their bight portions 44 are disposed on shoulders 47 immediately inwardly of the entrances 32 and at the remote ends of said entrances. Thus (see Fig. 16) the arm portions 45 and 46 of the respective contacts extend partly across the entrance slots 32 of the respective chambers. Screws 48 may pass through contact plate portions 42 and be threaded into sockets provided for them in the body and in addition binder post screws 49 are provided on the respective contact adjacent to recesses or notches 50 provided in the upper free edge of the body for the entrance of lead wires 51 and 52 thereto.

The contacts 40 and 41 or at least the arms thereof comprising the portions 45 and 46 are of spring metal. The wall 35 in its opposite sides in alignment with such spring arms is provided with grooves or slots 53 and 54 aligned with the entrance slots 32 and into which contact prongs may partly enter and by which such prongs may be partly guided as will appear. The portion of wall 35 comprising the inner end of the slot or groove 54, is about midway its ends and at a point substantially opposite where the arm of the contact bends to provide the portions 45 and 46, provided or formed with a horizontal shoulder 55. This shoulder enters into the locking together of the bases and plugs of the respective two part sockets as will be made clear. Binding post screws 49 are shown as threaded into nuts 56 (see Figs. 17 and 18) disposed in suitably shaped pockets opening through the L-shaped surfaces above mentioned.

The bases 18 and 20 are rigidly mounted in the fixture 10. To this end the latter is provided adjacent its respective ends (or in such spaced relation as is determined by the length of the lamp to be used) with a pair of openings or holes 57 and 58 of a size and shape to receive the neck portions 31 of the base bodies 30. As above suggested these holes are of a standard size in fixtures now in use and thus the bases 18 and 20

may be mounted on existing fixtures without difficulty. As mounted the necks 31 of the bases are located in the respective holes 57 and 58 and such necks are of lengths to bring their lower surfaces substantially flush with or slightly below the lower surface of wall 11 of the fixture.

Each of the bodies 30 is provided with a perforation 59 extending entirely therethrough and preferably, as shown, passing through the separating wall 35 between the chambers 33 and 34 of each base. The lower wall 11 of the fixture is provided with holes 60 registering with the holes 59 and a bolt 61 passes through such registering or aligning holes in the matter of each of the bases. On the upper side of each base is an insulating plate 62 resting on the upper edge of the wall 35 and on such plate is a metal plate 63. Bolts 61 pass through both such plates and threaded onto such bolts are nuts 64. Thus it will be seen that on tightening of nuts 64 on bolts 61 the bases are secured to the fixture 10 and as the rectangular neck portions 31 of such bases are held in similarly shaped holes in the lower wall of fixture 10 the bases are firmly mounted and held against turning or other movement relative to the fixture.

When the bases are mounted on the fixture as described the plugs 19 and 21 are simply applied to the lamp 12 and the latter mounted by connecting the plugs with the bases. This requires but a simple rectilinear movement of the lamp and the plugs. Referring now to the plug 19 shown in Figs. 4, 5, 8, 9, 10, 11 and 12 as well as in Figs. 1, 2 and 3, it is noted that the same includes a housing comprising a mounting body 65 and a cover 66. Mounting body 65 is of insulating material or the parts mounted on such body must be insulated therefrom and cover 66 since it is not engaged by any of the contact parts may be of insulating material or of metal as may be desired in any particular case for the purpose of ornamentation or the like.

Secured to the upper end portion of body 65 as by rivets 67 are a pair of contacts or prongs 68 and 69 projecting beyond the upper end of the plug 19 for insertion through the entrance slots 32 of base 18 and into engagement with the contacts 40 and 41 respectively of such base. Preferably body 65 is provided with elongated recesses receiving portions of the prongs whereby the latter are held against turning movement although other means may be used for that purpose. As here shown the rivets 67 are hollow and are internally tapped for the threading thereto of screws 70 used for securing the cover 66 to the body 65. If desired cover 66 may have counterbores 71 receiving the heads of said screws.

Body 65 mounts a pair of contacts 72 and 73 in spaced relation to the prongs 68 and 69 and these contacts are shown as tubular rivets passing through the body. The contacts are for the purpose of receiving the contact pins or tangs 24 and 25 at one end of the lamp 12 and are shown as so doing in Figs. 8 and 12. A screw 74 secures a contact member 75 to the inner side of body 65 and such member in addition to the portion held against the body by said screw includes an outwardly and upwardly extending free spring arm 76. Contact 73 is electrically connected with member 75 by a wire 77.

A bimetallic thermal element 78 has an arm 79 located under a lateral extension 80 of the prong 69 and an upwardly and outwardly curving portion the free end 81 of which is bent upon itself providing a hook-like portion. When the

lamp is in use the free end portion of the arm 76 is located under the hook-like portion of the bimetallic element 78 as shown by the full lines in Fig. 9. Thus it will be understood that wire 77 completes a circuit between rivet 73 and member 75 and that the circuit from the latter to the prong 69 is completed by the bimetallic element 78 when the latter is engaged with the free end 76 of member 75 as in Fig. 9.

From the contact 72 a wire 82 (shown as insulated) connects with a bent metal post 83 mounted by the body 65. Wire 82 may be electrically connected with post 83 but preferably is merely supported by said post and includes an exposed portion bent into a coil 84 extending between post 83 and a somewhat similar post 85 fixed to and in electrical contact with prong 68. With this arrangement it will be seen that contact 72 may be electrically connected with prong 68 through wire 82, coil 84 and post 85 although the actual connection as here shown is through the named parts and also the post 83.

The posts 83 and 85 have their upper ends bent to extend toward one another and thus support the coil 84 in spaced relation to the body 65 but also within the curved portion of the bimetallic element 78. This coil 84 is a heating coil and on the happening of certain things (as will appear) is adapted to influence the bimetallic element 78 to have the latter shift and release the free end portion 76 of the member 75 whereupon such end portion springs outwardly as to the dotted line position of Fig. 9.

A button 86 operates through an opening provided in the front wall of cover 66 and at the inner side of said cover is provided with a flange 87 whereby the button may not be moved outwardly entirely through the mentioned opening. At its inner end the button 86 bears against the arm or portion 76 of the member 75. Thus in the event the bimetallic element has become heated and released the said arm or portion 76 so that the latter has moved to the dotted line position of Fig. 9 it will be clear that when such element has cooled and returned to normal position the free end of arm 76 may be forced inwardly by the button 86 and will cam the element out of the way or snap past the hooked portion of the element to the under side thereof to be again held by said element in electrical engagement therewith.

Fig. 8 shows the prongs of plug 19 engaged with the contacts 40 and 41 of the base 18. There it is noted that these prongs are notched in their outer edges as at 88 toward their free ends and that the bent free arm portions of the contacts enter such notches. As the arm portions 45 are at the angle shown best in Fig. 16 the prongs may be easily forced through the entrances 32 and past the contact arms to the positions shown in Fig. 8. However, owing to the different and more pronounced inclination of the portions 46 of the contact arms withdrawal of the prongs from the base is resisted to a greater extent than is the insertion of such prongs. This is of some assistance in maintaining the plug 19 in connected relation with the base 18.

Additionally it is noted that the opposed edges of the prongs are provided with shoulders 89. In the present case the shoulder 89 on prong 68 is not used. The spring arm of contact 40 is stronger, in that it is heavier or of greater temper, or the like, than the corresponding arm of contact 41. Thus as the prongs are inserted into the base the spring arm of contact 40 tends

the prongs and the entire plug 19 toward the contact 41 bringing the shoulder 89 of prong 69 over the shoulder 55 on the dividing wall 35 of the base body. This provides a simple positive lock means preventing casual movement of the plug 19 from the base 18.

However, on a slight lateral movement of the plug in the opposite direction the spring arm of contact 40 is overcome and the shoulder 89 of prong 69 moved from over the shoulder 55 whereupon the plug may be withdrawn from the base subject only to frictional resistance as will be offered by the engagement of the spring contact arms with the prongs and particularly the resistance of the inclined arm portions 46 to movement of the prongs.

Plug 21 is quite similar to plug 19 and includes a body 90 of insulating material and a cover 91 which may or may not be of insulating material as desired. A pair of hollow rivets 92 (similar to the hollow rivets 67 of plug 19) secure a pair of the prongs 68 and 69 to the body 90 and are tapped for the reception of screws 94 which as in the case of the screws 70 may be insulated from the cover if the latter is not of insulating material and which serve to secure the cover to the body.

In addition a pair of contacts 95 and 96 comprising hollow rivets are mounted by the body and in fact pass therethrough for the reception of the contact pins or tangs 26 and 27 respectively of the lamp 12. A wire 97 connects contact 96 with a heater coil 98. A screw 99 secures a bimetallic thermal element 100 comprising a contact member to the body 90 and a wire 101 connects such element with the contact 95. Element 106 includes a free movable end portion 102 carrying a contact 103.

A second bimetallic contact element 104 has an arm 105 disposed beneath and anchored by and in electrical contact with the lateral extension 80 of the prong 69. Element 104 is substantially U-shaped and includes an outer arm 106 carrying a contact 107 normally engaged by the contact 103 whereby a circuit is normally closed between contact 95 and prong 69 by wire 104, element 100, and element 104.

The heater coil 98 is located in the bight portion of the bimetallic element 104 and is supported at its respective ends by posts 109 and 103 the former of which is supported by body 90 while the latter is supported by and in electrical contact with prong 68. These posts have their upper ends bent toward one another providing support for the coil and the latter through wire 97, and the posts 107 and 108 completes a circuit from contact 96 to prong 68. The particular relation and function of the elements 102 and 104 will later be given in detail but here it is noted that on heating up coil 98 will influence element 104 and the latter will tend to open or its arm 106 will tend to move away from arm 102 of element 100 thereby separating the contacts 103 and 107.

The action of the spring arm of the contact 40 on the prong 69 when the plug 21 is connected with the base 20 as in Figs. 20 and 21 will it is believed be clear. However, it is pointed out that such contact arm will tend to shift the prong 69 and thus the entire plug 21 laterally to dispose the shoulder 89 of such mentioned prong over the shoulder 55 on the dividing wall 35 of the base body whereby to prevent rectilinear movement of the plug away from the base, in effect providing a positive lock between the

plug and base as in the case of the plug 19 and its base 18.

It is believed that an understanding of the circuit shown in Fig. 22 will help in the reading of an explanation of the operation and advantages of the device the structure of which has heretofore been set forth in detail. Referring now particularly to the wiring diagram (Fig. 22) the parts therein have been given the same reference 10 identifications as in the other figures of the drawing. However, some additional parts are shown in the wiring diagram.

A wire 115 has been added to complete the circuit from bimetallic element 78 to prong 69 of the plug 19 and a similar wire 110 has been added to complete the circuit from element 104 of the plug 21 to the prong 69 of such plug. Thus the wires 115 and 110 are used in the diagram to show the connections actually made by the clamping of the mentioned bimetallic elements under the lateral extensions 80 of the prongs 69 of the respective plugs. Additionally a three element condenser 111 is shown as connected across the post 108 and the added wire 110 with the intermediate element of said condenser grounded. This is to prevent radio broadcasting by the lamp 12 as will later be again mentioned.

On closing of switch 13 to start the lamp the circuit may be through wire 112 to wire 52, contact 40 of plug 19, prong 69, wire 115, element 78, member 75, wire 77, contact 73, contact pin or tank 25, filament 28, contact pin or tank 24, contact eyelet 72, wire (or post) 82, heater coil 84, wire (or post) 85, prong 68, contact 41 of plug 19 and wire 51 to contact 40 of base 22, prong 29 of plug 21, wire 110, element 104, element 100, wire 101, contact eyelet 95, contact pin or tang 27, filament 29, contact pin or tang 26, contact eyelet 96, wire 97, heater coil 98, wire or post 105, prong 68 of plug 21, contact 41 of base 22 and return wire 113 having therein any or the usual ballast 114.

The circuit being as described the filaments 28 and 29 will be heated and will heat the contents of the lamp tube to form a conductive vapor. After a predetermined time interval the heater coil 98 causes the bimetallic element 104 to move the contact 107 out of engagement with contact 103 thus opening the line circuit. Now if the lamp has been sufficiently heated the current will flow from filament 28 across the lamp to filament 29 and through wire 97, coil 98, prong 68 of plug 21, contact 41 of base 22, return wire 113 and ballast 114. Under these circumstances elements 75 and 78 remain in contact and the circuit to filament 28 is through them. On opening of switch 13 the lamp is extinguished.

The element 102 and 104 together with the heater coil 98 and associated parts constitute a starter. Filaments 28 and 29 must be heated to a glow for a sufficient time before the running voltage is impressed on the lamp to obtain lighting. Present devices used for the purpose of controlling the time of glow of the filaments do not function to give a reasonably immediate light when the lamp is cold, as in a temperature of 40 degrees F. or less. The glow is not maintained for a sufficient length of time. The devices used are thermal relays comprising a source of heat, a fixed contact and a piece of bimetallic thermostatic metal carrying a contact.

The socket 17 has the present starter mounted therein and the latter includes a thermal relay which glows the filaments for a relatively long time to favor lighting of the lamp at low ambient

temperature. The present thermal relay includes the added piece of relatively stiff metal 102 carrying the contact 103. Lost motion between member 102 and the thermal element 104 accounts for a delay in the operation of the relay to the end that the glow of the filaments 28 and 29 is maintained for a longer time.

Member 102 is of stiffer metal to smooth out the jerkiness of the thermo-metal in the relay. This smoothness makes for superior operation of the contacts, which are prone to arc and weld if opened and closed in a jerky manner. This added stiffer member 102 is of bimetal but only for the purpose of keeping its relative position both to the element 104 and its contact constant despite varying ambient temperatures. During operation of the lamp the present thermal relay is held open by the running current of the lamp (through coil 98) rather than by by-passed current as with the devices heretofore in use.

Glowing of the filaments prior to lighting of the lamp takes a comparatively large current. The current to the lamp is throttled by the impedance or ballast 114 and the latter becomes hot if called upon to supply, for more than a short time, electricity in addition to that required to keep the lamp lighted. The life span of the lamp is reached when the filament loses its electrifying power. Then the automatic starter above described and those at present in use will make the filaments glow but the lamp will not light whereupon as the starter heats up and then cools off it will make the filaments glow and glow again in an effort to start the lamp. These repeated attempts to start an exhausted lamp result in a considerable waste of electricity in addition to which the ballast heats up and a fire hazard develops.

The present invention includes means to control the successive attempts of the starter to start the lamp. Such means comprises the member 75, the bimetallic element 78, the heater coil 84, and the associated parts. This means is mounted in plug 19 of socket 16. Such means accumulates heat from the successive attempts to start a lamp with an inert (deactivated) filament to the end that element 78 shifts from the full line to the dotted position of Fig. 9 and the free end portion 76 of member 75 moves from under and out of contact with the said element permanently opening the circuit to cut the supply line of electricity. It is preferred that the parts be constructed and arranged to permit of the starter making several attempts to start a lamp. The time of movement of element 78 to open circuit position depends on the closeness of its relation to heater coil 84, the thickness of the element, etc.

Attention is directed to the fact that the thermal bimetallic element 78 is both a switching member and a latching member. When the lamp is removed from the fixture 10 for replacement the socket plug 19 is removed along with the lamp. Then when a new lamp is provided the said plug is convenient to the party making the change of lamps. He presses the button 86 forcing the arm 76 of member 75 inwardly to again snap into position under the hook-like portion 81 of the bimetallic element which in the meantime has cooled off and returned to normal condition and position.

The present invention provides means whereby a lamp may be easily changed. The fluorescent lamp is efficiently operative for about 2000 hours. Changing lamps every 100 to 200 days and tem-

porary removal between times for cleaning is a serious matter in plant economy. The handling of the lamp, a glass tube from three to six feet in length, at places 15 to 20 feet above a floor cluttered with machinery, show cases, and the like is an awkward and hazardous job. The job is made extra difficult owing to the necessity for fitting the extremely small contact pins or tangs at the ends of the lamp into equally small slots or recesses in fixed sockets built into fixtures.

The present invention includes the mounting of the lamp by a pair of two part sockets. The plugs are attached to the lamp by placing them against the ends of the lamp with the contact pins or tangs of the latter in the contact eyelets of the plugs. There is a rather snug fit of the contact pins or tangs in the contact eyelets. Following mounting of the plugs on the ends of the lamp the latter is mounted on the fixture substantially by a rectilinear movement involving inserting the prongs of the plugs through the entrances 32 of the bases into engagement with the contacts 40 and 41 within such bases.

A slight lateral movement of the lamp and plugs takes place after the prongs are in the bases to hook the shoulders 89 of the prongs 69 over the shoulders 55 on the dividing walls of the bases. This provides a positive lock so that there is no danger of the lamp casually dropping from the fixture or being jarred from the latter. A positive lateral movement to carry the shoulders 89 from over the shoulders 55 is required before the prongs may be withdrawn from the bases. An important feature is the firm connection between the contact eyelets of the sockets and the pins or tangs of the lamp.

The fluorescent lamp found ready acceptance in weaving and other textile plants. Its low external temperature allowed it to be put into desirable locations denied to the hot incandescent lamp. However, the fixed sockets involved exposed live conductors to the ambient lint and created a fire hazard. In locales where the atmosphere is gas laden short circuiting and increased maintenance cost occurs. The present sockets include holes rather than slots for the reception of the pins or tangs of the lamp and thus there are no exposed parts as the pins or tangs have rather snug fits in the eyelet type contacts. Such a construction would be impractical if not impossible with fixed socket constructions as heretofore used.

The sockets heretofore used for mounting of fluorescent lamps were rigidly mounted in the fixtures. The design of such sockets was fixed. Esthetic difference among lamp designers cannot be met in a fixed design made primarily for utilitarian purposes. In the present socket the part exposed to the eye is merely a cover. It has no part in the functioning of the socket and accordingly may be made in various shapes, of various materials and in desired colors, etc.

The usual starter for a fluorescent lamp is a fragile device attached to the lamp fixture by some means especially provided for that purpose. The starter is not usually accessible and when the starter is to be replaced the lamp must first be removed. In the present case the starter is in one of the sockets and in the part of such socket 78 removable with the lamp. Thus the present starter is easily accessible. Further the present starter is of a hardy construction and of heavier wire so that it carries the operating current of the lamp and has indefinite life. The time required for opening of the present starter may be

varied by having the element 104 closer to or farther from the heater coil 98 and by varying the thickness of the metal of the parts etc. As the starter is within the plug of a lamp socket no extra part for the mounting of the starter is required.

In the constructions heretofore in use neither the lamp nor the starter can be removed by extension means. The complicated engagement of the small terminal pins or tangs of the fluorescent lamp with the equally small channels in the fixed sockets is a safe matter only when the hands are actually grasping the lamp. In the present construction the lamp may be applied or mounted by extension such as that shown in my companion application above mentioned and in addition the lamp together with the plugs of the respective sockets may be removed from the fixture by extension means since only a slight lateral movement is needed after which a straight outward pull separates the parts.

As the fluorescent lamp sets up "static" it has been proposed to include small two element condensers in the starter. The effectiveness of such constructions is very limited. In the present instance the three element condenser 111 is mounted in one of the bases and the third element of such condenser is grounded as to the fixture 10 or the attaching bolt 61 contacting such fixture. This is an effective means for suppressing radio interference by the lamp 12.

Having thus set forth the nature of our invention, what we claim is:

1. In a fluorescent lamp socket, a base and a plug separable from said base, contacts in said base, said base having entrances to said contacts and a shoulder therein and at one side of and facing away from one of said entrances, said plug having openings to receive the contact pins at one end of a fluorescent lamp, prongs on said plug and insertable through said entrances into engagement with the contacts of the base, means for electrically connecting said prongs with lamp contact pins inserted through said openings, one of said prongs having an outwardly facing shoulder, and spring means in said base at the side of the entrance opposite said shoulder for moving said plug and base relatively on insertion of the prongs of the former into the latter to dispose the prong carried shoulder over the first mentioned shoulder and thereby provide means to prevent casual separation of the plug from the base.

2. The combination as in claim 1 wherein said spring means comprises one of the contacts in said base.

3. A fluorescent lamp socket comprising a base and a plug separable from said base, contacts in said base and entrances leading to said contacts, prongs on said plug and insertable through said entrances into engagement with said contacts, a pair of contacts on said plug portion for detachable engagement with the contact pins on the end of a fluorescent lamp, means mounted on said plug including a heater coil connecting one of said pair of contacts with one of said prongs, and means within said plug and including a thermally operable starter switch located to be influenced by said heater coil and electrically connecting the other of said pair of contacts with another of said prongs.

4. A fluorescent lamp socket comprising a base and a plug separable from said base, contacts in said base and entrances leading to said contacts, prongs on said plug and insertable through said entrances into engagement with said contacts, a

pair of contacts on said plug for detachable engagement with the contact pins on the end of a fluorescent lamp, means mounted on said plug including a wire and a heater coil connecting one of said pair of contacts with one of said prongs, and means within said plug and including a wire and a thermally operable starter switch located to be influenced by said heater coil and electrically connecting the other of said pair of contacts with another of said prongs.

5. A fluorescent lamp socket comprising a base and a plug separable from said base, contacts in said base and entrances leading to said contacts, prongs on said plug and insertable through said entrances into engagement with said contacts, a pair of contacts on said plug for detachable engagement with the contact pins on the end of a fluorescent lamp, means mounted on said plug and including a heater coil connecting one of said pair of contacts with one of said prongs, means including a thermally operable starter switch mounted on said plug and located to be influenced by said heater coil and electrically connecting the other of said pair of contacts with another of said prongs, said thermally operable starter switch comprising a substantially U-shaped bimetallic element, said heater coil located between the arms of said element, a contact on one of the arms of said element, a member, a contact on said member and located to be engaged by the contact on said arm, and said member of bimetal whereby to keep its contact in engagement with that of said arm under various conditions of ambient temperature.

6. A fluorescent lamp socket comprising a base and a plug separable from said base, said plug comprising a body, a pair of prongs on said body, a pair of contacts on said body and adapted to be engaged by the contact pins on the end of a fluorescent lamp, means mounted on said body including a heater coil connecting one of said pair of contacts with one of said prongs, means mounted on said body including a thermal switch connecting the other of said pair of contacts with another of said prongs, and said switch located to be influenced by said heater coil and constructed and arranged to open and thereafter stay open on predetermined heating of said coil.

7. A fluorescent lamp socket comprising a base and a plug separable from said base, said plug comprising a body, a pair of prongs on said body, a pair of contacts on said body and adapted to be engaged by the contact pins on the end of a fluorescent lamp, means including a heater coil on said plug and connecting one of said pair of contacts with one of said prongs, means including a thermal switch on said plug and connecting the other contact of said pair with the other prong, said switch comprising an arm and a bimetallic element, said element having one of its end portions anchored and having its other end portion partly bent about said heater coil, the free end of the last mentioned end portion of said element comprising a hook adapted to be disposed over the free end of said arm in electrical contact therewith, and said arm comprising a spring arm whereby on movement of said element due to heating by said coil the arm springs out of position and away from the element to open circuit relation therewith.

8. A fluorescent lamp socket comprising a base and a plug separable from said base, said plug comprising a body, a pair of prongs on said body, a pair of contacts on said body and adapted to be engaged by the contact pins on the end of a

fluorescent lamp, means including a heater coil on said plug and connecting one of said pair of contacts with one of said prongs; means including a thermal switch on said plug and connecting the other contact of said pair with the other prong, said switch comprising an arm and a bimetallic element, said element having one of its end portions anchored and having its other end portion partly bent about said heater coil, the free end of the last mentioned end portion of said element comprising a hook adapted to be disposed over the free end of said arm in electrical contact therewith and said arm comprising a spring arm whereby on movement of said element due to heating by said coil the arm springs out of position and away from the element to open-circuit relation therewith, and a manual for forcing said arm back into hooked circuit closing relation with said element on cooling of the latter.

9. A fluorescent lamp socket comprising a base and a plug separable from said base, said plug comprising a body, a pair of prongs on said body, a pair of controls on said body and adapted to be engaged by the contact pins on the end of a fluorescent lamp, means mounted on said body including a wire and a heater coil connecting one of said pair of contacts with one of said prongs, means mounted on said body including a wire and a thermal switch located to be influenced by said heater coil and connecting the other of said pair of contacts with another of said prongs, and said switch constructed and arranged to open and thereafter stay open on predetermined heating of said coil.

10. In a base for a separable two part fluorescent lamp socket, said base comprising a body of insulating material having a pair of chambers therein and narrow elongated entrance slots leading to the respective chambers, contacts in the respective chambers and each comprising a spring arm including a bent portion inclining inwardly of said body and lying partly across the entrance slot to its chamber from the narrow edge of said slot, each of said spring arms also including a portion extending from the inner end of the first mentioned portion and inclining inwardly of the body and away from the entrance slot to its chamber but at a greater angle to the plane of the entrance slot than the angle of the first mentioned portion to such plane whereby flat contact prongs having notches in their edges to receive the junctures of the arm portions may more easily cam aside the arms as such prongs enter the chambers and engage the first mentioned inclining arm portions than as the prongs are withdrawn from engagement with the inner surfaces of the second mentioned inclining arm portions.

11. A fluorescent lamp socket comprising a pair of separable parts, a pair of contacts on one of said parts and adapted to be detachably engaged by the contact pins on the end of a fluorescent lamp, means mounted on said body to connect said pair of contacts in a fluorescent lamp circuit when said pair of socket parts are connected, said means including a heating coil in circuit with one of the contacts of said pair and a thermal switch in circuit with the other contact of said pair and located to be influenced by said heating coil, and said switch constructed and arranged to open and stay open on predetermined heating of said coil.

12. A fluorescent lamp socket comprising a pair of separable parts, a pair of contacts on one

of said parts and adapted to be detachably engaged by the contact pins on the end of a fluorescent lamp, means mounted on said body to connect said pair of contacts in a fluorescent lamp circuit when said pair of socket parts are connected, said means including a heating coil in circuit with one of the contacts of said pair and a thermally operable starter switch in circuit with the other contact of said pair and located to be influenced by said heating coil, and said starter switch constructed and arranged to open on predetermined heating of said coil and to automatically close on cooling following such opening.

13. A fluorescent lamp socket comprising a pair of separable parts, a pair of contacts on one of said parts and adapted to be detachably engaged by the contact pins on the end of a fluorescent lamp, means mounted on said part to connect said pair of contacts in a fluorescent lamp circuit when said pair of parts are connected, said means including a heater in circuit with one of said contacts and a thermally operable starter switch in circuit with the other of said contacts, said starter switch comprising a substantially U-shaped bimetallic element straddling said heater, a contact on an arm of said element, a member, a contact on said member and located to be engaged by the contact on said arm, and said member of bimetal whereby to keep its contact in engagement with that of said arm under various conditions of ambient temperature.

14. A fluorescent lamp socket comprising a pair of separable parts, a pair of contacts on one of said parts and adapted to be detachably engaged by the contact pins on the end of a fluorescent lamp, means mounted on said one of said parts to connect said pair of contacts in a fluorescent lamp circuit when said socket parts are connected, said means including a heating coil in circuit with one of the contacts of said pair and a thermally operable starter switch in circuit with the other contact of said pair, said starter switch comprising a bimetallic element located to be influenced by said heating coil, a contact on said element, a member including a strip anchored at one end and at its other end carrying a contact positioned to be engaged by the contact of the element as the latter cools, and said strip of bimetal whereby to keep its contact in engagement with that of said element under various conditions of ambient temperature.

15. A fluorescent lamp socket comprising a pair of separable parts, a pair of contacts on one of said parts and adapted to be detachably engaged by the contact pins on the end of a fluorescent lamp, means mounted on said one of said parts to connect said pair of contacts in a fluorescent lamp circuit when said pair of socket parts are connected, said means including a heater in circuit with one of said contacts of the pair and a thermally operable starter switch in circuit with the other contact of said pair, said starter switch comprising a bimetallic element located to be influenced by said heater, a contact on said element, a member including a strip anchored at one end and at its other end carrying a contact positioned to be engaged by the contact of the element, said member positioned to have its contact engaged by the contact of the element as the latter cools, and said member stiff to keep its contact in engagement with that of the element on initial heating of the latter by said heater.

16. A plug for a fluorescent lamp socket including a base and a plug, said plug comprising a

substantially flat body of insulating material, contacts on the outside of said body, said body having entrances from its inner side for the insertion of the end terminals of a fluorescent lamp into engagement with said contacts, a pair of prongs secured against the outer side of the body and projecting beyond one edge thereof, a heater at the outer side of the body and mounted thereon and connected with one of said contacts and one of said prongs, a thermally operable switch on the outer side of the body and connected with the other of said contacts and the other of said prongs, said switch located to be influenced by said heater, a hollow cover on the outer side of said body and enclosing said contacts, heater, switch and portions of said prongs, and means removably securing said cover to said body.

17. A plug for a separable fluorescent lamp socket including a base and a plug, said plug comprising a substantially flat body of insulating material, contacts on the outer side of said body, said body having entrances from its inner side for the insertion of the end terminals of a fluorescent lamp into engagement with said contacts, a pair of prongs secured against the outer side of said body and projecting beyond one edge thereof, a heater on the outer side of said body and connected with one of said contacts and one of said prongs, a thermally operable switch on the outer side of the body and connected with the other of said contacts and the other of said prongs, said switch located to be influenced by said heater, a hollow cover on the outer side of said body and enclosing said contacts, switch, heater and portions of said prongs, means removably securing said cover to said body, and a push button mounted by said cover and operable from the outer side thereof to close said switch.

18. In a plug for a separable two part fluorescent lamp socket, said plug comprising a substantially flat body of insulating material, a pair of contact prongs secured against the outer side of said body and extending beyond an edge thereof, a pair of contacts on said side of the body and electrically connected with the respective prongs, said body having openings therethrough for the insertion of the end terminals of a fluorescent lamp from the inner side of the body into engagement with said contacts, a hollow cover over the outer side of said body and enclosing said contacts and portions of said prongs, and means removably securing said cover to said body.

19. A two part socket for a fluorescent lamp, said socket including a base portion and a plug portion, contacts in said base portion, said base portion having entrances leading to said con-

tacts, contact prongs on said plug portion and adapted to be inserted through said entrances into engagement with said contacts, a pair of contacts in said plug portion in spaced relation to said prongs, said plug portion having entrances leading to said contacts and providing for the insertion of the terminal contact pins into said plug portion in engagement with the contacts therein, a starter switch in said plug portion and including contacts movable to and from engagement and connected respectively with one of said plug contacts and one of said prongs and a heater element associated with and adapted to influence movement of said contact and connected with the other of said plug contacts and the other of said prongs.
